(57) **CLAIM**

The ornamental design for a broom, as shown and described.

DESCRIPTION

FIG. 1 is a perspective view of the broom of the present invention;

FIG. 2 is a reduced side elevational view of the broom of FIG. 1; and,

FIG. 3 is a reduced top plan view of the broom of FIG. 1. The broken lines showing a handle are for illustrative purposes only and form no part of the claimed design.
